(57) **CLAIM**

The ornamental design for an injection site protector, as shown and described.

DESCRIPTION

FIG. 1 is a top perspective view of the present invention as it is applied to a patient's arm.

FIG. 2 is a top view of the present invention as it appears before being applied.

FIG. 3 is a top view of the present invention of FIG. 2 in a sterile package.

FIG. 4 is a side view of the present invention shown in the direction of line 4—4 of FIG. 3; and,

FIG. 5 is a side view of the present invention shown in the direction of line 5—5 of FIG. 3.

The broken line showing of environmental structure in the figures is for illustrative purposes only and forms no part of the claimed design.

1 Claim, 2 Drawing Sheets

FIG. 3

FIG. 4

FIG. 5
